(57) **CLAIM**

The ornamental design for a frozen confection drip catcher, as shown and described.

DESCRIPTION

FIG. 1 is a left rear perspective view of a frozen confection drip catcher having an embossed facial image incorporated thereon, illustrative of my new design:

FIG. 2 is a top plan view thereof illustrative of my new design;

FIG. 3 is a bottom plan view thereof illustrative of my new design;

FIG. 4 is a front elevational view thereof illustrative of my new design;

FIG. 5 is a rear elevational view thereof illustrative of my new design;

FIG. 6 is a left side elevational view thereof, the right side elevational view being a mirror image thereof illustrative of my new design;

FIG. 7 is an enlarged, cross-sectional view showing the contour of a portion of the embossed image, taken along the line 7—7 of FIG. 2 illustrative of my new design;

FIG. 8 is an enlarged, cross-sectional view showing a hole that is adapted for receipt of a conventional confection stick therethrough, taken along the line 8—8 of FIG. 2 illustrative of my new design; and,

FIG. 9 is an enlarged, cross-sectional view showing the contour of another portion of the embossed image, taken along the line 9—9 of FIG. 2 illustrative of my new design; The broken lines are for illustrative purposes only and form no part of the claimed invention.
